Charles F. B. Jr.

1
Inventor
CHARLES R. FARGO.
By Charles R. Fargo Atty.

UNITED STATES PATENT OFFICE.

CHARLES R. FARGO, OF CHICAGO, ILLINOIS, ASSIGNOR TO WILSON-JONES LOOSE LEAF CO., OF CHICAGO, ILLINOIS, A CORPORATION OF ILLINOIS.

LOOSE-LEAF BINDER.

Application filed May 15, 1918. Serial No. 234,611.

To all whom it may concern:

Be it known that I, CHARLES R. FARGO, a citizen of the United States, and a resident of the city of Chicago, in the county of Cook and State of Illinois, have invented certain new and useful Improvements in a Loose-Leaf Binder; and I do hereby declare that the following is a full, clear, and exact description of the same, reference being had 5 to the accompanying drawings, and to the numerals of reference marked thereon, which form a part of this specification.

My invention has reference more particularly to the clamp plate or shell to which 15 the binder posts or other connecting means are attached for holding the leaves in place, and also has reference to the hinge connection whereby the cover of the binder is attached to the clamp plate.

20 The object of my invention is to provide a clamp plate or shell that can be easily and economically made from sheet metal so as to provide a strong, durable construction.

Another object of my invention is to provide 25 a clamp plate or shell having a member integral therewith at each end whereby a simple and inexpensive closure is provided at each end of the clamp plate, flush with the walls thereof.

30 Another object is to provide a tubular clamp plate having a longitudinal opening whereby access is had to the interior of the plate and which has a separate plate attached thereto for covering the longitudinal opening.

Another object of my invention is to provide 35 a tubular clamp plate and a separate plate attached thereto having a hinge whereby the cover of the binder is pivotally connected with the clamp plate.

Another object of my invention is to provide 40 a tubular clamp plate with a longitudinal opening whereby access is had to the interior of the clamp plate and a separate plate which is attached thereto and serves 45 to cover the longitudinal opening and also to provide a hinge whereby the cover of the binder is pivotally connected with the clamp plate.

50 It is further an object of my invention to provide a clamp plate with a hinge member adjacent the outer face and a hinge member on the cover of the binder connected there-

with and arranged to permit the cover to fold over flat against the outer face of the 55 clamp plate.

My invention also has other important objects which will appear from the following specification and the accompanying drawings, wherein I have illustrated and de- 60 scribed a preferred form of my invention.

On the drawings:

Figure 1 is a perspective view of a complete loose leaf binder embodying my im- 65 provements.

Figure 2 is an enlarged inside view of the clamp plate or shell with a fragmentary portion of the cover attached and shows one end of the clamp plate in section.

Figure 3 is a sectional view on the line 70 3—3 of Figure 2.

Figure 4 is an enlarged sectional view on the line 4—4 of Figure 2.

Figure 5 is an enlarged sectional view on the line 5—5 of Figure 2. 75

As shown on the drawings:

The clamp plate or shell consists of a sheet metal blank which is bent longitudinally in the form of a tubular shell 1, and has an ear 2, integral therewith at each end which is 80 bent upwardly to form a closure or end wall for the shell. The inner upwardly turned flange 3, extends almost to the top of the end plates 2, and the opposite side wall 4, of the sheet metal member 1, is turned up as 85 shown, with a somewhat long radius of curvature between the bottom wall and the side wall so as to provide a rounded edge for the shell, and the upper edge of the wall 4, is turned inwardly as at 5, and terminates 90 adjacent the center of the shell. For providing a closure similar to the flange 5, for the other side of the shell, and also to provide a hinge for connecting the cover 6, to the shell, there is an angular plate 7, which 95 lies flat against the outer face of flange 3, as shown and has the flange 8, which extends inwardly toward the flange 5, and terminates at a distance therefrom so that a slot 9 is provided between the flange 8, and the flange 100 5, extending the entire length of the shell, said slot being of suitable width to admit the posts which connect the two clamp plates of the binder. The angle plate 7 is welded or otherwise permanently secured to the 105 wall 3 of the shell, and the end edges of the

flange 8, together with the end edges of the flanges 3, 4 and 5, are welded or otherwise secured to the edges of the end plates 2, so as to provide a strong structure. The edge 5 of the flange 7, adjacent the outer face of the shell 1, has a plurality of spaced loops 10, and the cover 6 has a reinforcing plate 11, adjacent the inner face of the cover, the edge of which projects from the inner edge 10 of the cover 6, and is bent on an oblique angle as at 12, and has complementary hinge loops 13, which are adapted to be inserted between the hinge loops 10 of the plate 7, and be connected therewith by means of the hinge rod 14, which is inserted through the loops 10 and 13, so that the cover 6 is hinged to the shell 1, and may be folded over flat against the outer face of the clamp plate 1. The thickness of the cover, as may be seen 20 by inspecting Figure 1 and comparing it with Figure 4, is not enough to bring the outer surface of the cover into the same plane as the outer surface of the clamp member. It is not even enough to bring the 25 outer surface of the cover into the plane of the axis of the hinge, but the inner margin of the outer surface of the cover will contact with the outer surface of the clamp member when the hinge illustrated in Figure 4 is moved through approximately 180°.

The tubular construction of the clamp plate 1 provides space therein for reinforcing or clamping members for securing the posts of the binder to the clamp plate 35 and any suitable structure may be employed for this purpose. For the purpose of illustration however I have shown a clamping member which consists of the block 15, which is of suitable size to fit in the shell 1, and may be inserted therein through the side 40 opening in the shell before the plate 7 is attached or otherwise, and this block is provided with a perforation 16, in line with the slot 9 of the shell through which the post of the binder may be inserted. This block 15 has an angular groove 17, at one side of the 45 opening 16, within which a ball 18 is adapted to operate to engage the post 19 of the binder and lock the binder plate in any position of adjustment on the post. A lever 20 is pivoted on a bracket plate 21 attached to the block 15, and engages the ball 18, for operating the same, and there is a button 22 pivoted to the lever 20 which projects 50 through a perforation in the outer wall of the shell 1, whereby the latch or lock for engaging the post may be released, the said lever being held in the normal locking position by the spring 23.

60 In constructing the binder the blocks 15 are placed in the shell and adjusted to the position which gives the desired spacing of the posts, and the blocks are then spot-welded or otherwise securely fastened in the adjusted position. The shell 1 has a perfora-

tion in the outer wall for the button 22, and may be provided with a perforation in the outer wall to register with the perforation 16, in the block to permit the post 19 to project entirely through the shell 1.

70 While I have illustrated and described my invention in a certain form, I am aware that various changes and modifications may be made without departing from the principles of my invention, and I therefore do not 75 purpose limiting the patent granted hereon otherwise than necessitated by the prior art.

I claim as my invention:

1. In a loose leaf binder the combination of a clamp member comprising a plate bent 80 longitudinally to form an elongated hollow shell, an angle member secured thereto and forming a wall therefor, said plate having an ear at each end integral therewith and bent transversely thereof to close the end of 85 the shell.

2. In a loose leaf binder the combination of a clamp member comprising a plate bent longitudinally to form an elongated hollow shell having an open slot therein, an angle 90 member secured to said plate forming one side of said slot, a plate at each end formed in accordance with the transverse outline of the shell and secured to the end edges thereof to provide a flush closure for the ends of 95 the shell.

3. In a loose leaf binder the combination of a clamp member comprising a plate bent longitudinally to form an elongated hollow shell having the longitudinal edges thereof 100 spaced to provide a longitudinal slot in the inner face of the clamp member, means for closing each end of the shell, and an auxiliary plate secured to the hollow shell and partially extending over the slot in the inner face thereof.

4. In a loose leaf binder the combination of a clamp member comprising a plate bent longitudinally to form an elongated hollow shell, a longitudinal hinge plate secured to 110 the hollow shell and a binder cover hinged thereto.

5. In a loose leaf binder the combination of a clamp member comprising a plate bent longitudinally to form an elongated hollow shell having the longitudinal edges spaced 115 to provide a longitudinal slot in the inner face of the clamp member, a longitudinal hinge plate secured to the hollow shell and projecting over the slot in the inner face thereof, and a cover for the binder hinged to the said hinge plate.

6. In a loose leaf binder the combination of a clamp member comprising a plate bent longitudinally to form an elongated hollow shell having the longitudinal edges thereof spaced to provide a longitudinal slot in the shell, a longitudinally bent plate secured to one side of the elongated shell and overlying 120 the slot, said plate being provided 125

with a hinge member along the edge thereof, and a binder cover pivotally connected with said hinge member.

7. In a loose leaf binder the combination 5 of a clamp member comprising a plurality of longitudinal plates suitably bent longitudinally and secured together to form a hollow shell, one thereof having a single right angle bend therein, a binder cover 10 pivotally attached to the shell and post engaging means secured within the shell for engagement with the binder posts for holding the clamp member in place.

8. In a loose leaf binder, the combination 15 of an elongated clamp member having an outer face and an inner face, the latter adjoining the leaves of the binder, a binder cover, and a hinge including a part connected to the clamp member and a part connected to the binder cover, the axis of the 20 hinge being located near the planes of the outer surfaces of the binder cover and clamp member whereby the cover can rotate through approximately 180° into contact with the outer face of the clamp member.

9. In a loose leaf binder the combination 25 of an elongated clamp member having an outer face and an inner face spaced therefrom and adapted to bear against the leaves of the binder, a binder cover, a hinge flush with the outer face of the clamp member, and a reinforcing plate on the inner face of the binder cover having an outwardly extending angularly offset portion pivotally 30 connected with the hinge so as to permit the cover to fold over against the outer face of the clamp member.

10. In a loose leaf binder, a clamp mem-

ber in the form of an elongated hollow shell 40 having a slot extending along the length of its inner face, including an outer plate bent longitudinally and an angle member secured thereto and forming part of the inner wall thereof.

45

11. In a loose leaf binder, the combination of a clamp member in the form of an elongated hollow shell having a slot extending along the length of its inner face for the reception of the binder posts, including 50 an outer plate bent longitudinally, an angle member secured thereto and forming part of the inner wall thereof, and hinge lugs integral with said inner angle member.

12. In a binder, a cover, a plate secured 55 to the face of said cover, a portion integral with and at an oblique angle to said plate and carrying ears, a clamping member, ears secured to said clamping member and aligned with the first-named ears, a 60 pintle through said ears whereby the clamping member and cover are hinged together, the axis of said hinge being behind the rear edge of the cover and outside the outer face of the cover whereby no obstacle is presented to the hinge motion of said cover until its outer face contacts with the outer face of the clamping member at which time the cover will be open and approximately 65 parallel to its closed position.

70

In testimony whereof I have hereunto subscribed my name in the presence of two subscribing witnesses.
